DAYLIGHT DEVELOPING TANK FOR ROLL
FILM HAVING PAPER PROTECTIVE STRIPS

Michael Lesjak, deceased, late of Goggingen, Germany, by Babette Viktoria Lesjak, executrix, Goggingen, Germany

Application November 26, 1951, Serial No. 258,178

Claims priority, application Germany
November 25, 1950

8 Claims. (Cl. 95—90.5)

1

The present invention relates to a daylight developing tank for roll films having paper protective strips, wherein the roll film is placed in a preliminary supply chamber and from there is introduced into an adjacent developing chamber by pulling out the protective paper strip. More particularly, it concerns means whereby the leading end of the film will become automatically affixed to the take-up axle in the developing chamber.

Daylight developing tanks have long been known. A very successful form is described in the U. S. Patent No. 2,082,962, issued to Lesjak et al. However, in this known apparatus, it was necessary, in order to introduce the film edges into the spiral grooves in the opposed flanges on the take-up axle, to press the edges of the film slightly together and to guide it to the inner end of the spiral by means of a swingable guide. The thus narrowed film was pulled between the spirally grooved flanges to the axle with the aid of a pull-in band and a clamp.

The main object of the invention is to dispense with the spirally grooved flanges, the means for narrowing the film, and, above all, the pull-in band of the known apparatus. It has been found that this can be accomplished if one provides a film attaching means directly upon the take-up axle and means whereby the leading end of the film will automatically be guided to such attaching means and grasped thereby.

According to the invention means are provided in the daylight developing tank that guide the film as it enters the developing chamber upon pulling off the protective paper strip, into an open film attaching means such as a clamp, located directly on the take-up axle. The means so provided for conducting the leading end of the film to the film attaching means on the take-up axle consist of a stripping device for unrolling the film in the supply chamber and a sliding support arranged between the supply chamber and the take-up axle. This sliding support is swingably mounted near the upper edge of the partition dividing the supply and developing chambers and projects into the opening of the film attaching means on the take-up axle. The sliding support, after the introduction of the film end into the attaching device and upon rotating the take-up axle in a counterclockwise direction, drops aside by its own weight and automatically frees the film winding space within the developing chamber.

The film attaching device upon the take-up axle preferably consists of a single clamp jaw that closes against the axle, and which, upon

2

turning of the axle, is pressed against it automatically by suitable means, such as a bowed rod, also on the axle. Said rod may have a projecting end which, when the film clamping device is in open position and the axle is turned in a counterclockwise direction, strikes against a part of the developing chamber, thereby automatically reversing the position of the bow. The film attaching means on the take-up axle may, however, if desired, also be closed manually from outside of the tank. Conveniently, the projecting end of the rod also extends to strike another projection of the developing chamber, thus, preventing the winding of the film in the wrong direction, i. e. clockwise, at the beginning of the winding procedure. For it is essential that the take-up axle be first turned in a counterclockwise direction, so that the swingable sliding support may drop aside and the film be loosely wound about the axle with its emulsion side outwards.

There may also be provided a clamping device inside the cover of the tank for holding the trailing end of the film. However, this is not essential, since the end of the film is firmly attached to the paper protective strip, so that it cannot be drawn into the interior of the developing chamber. Such a clamping or holding device is preferably adjustable in various positions and may also serve, while partly open, to assist in guiding the film end to the film attaching means on the take-up axle.

The cover of the daylight developing tank according to the invention is preferably made of two overlapping parts between which the paper protective strip may be pulled out. The passage between the overlapping parts should begin in the neighborhood of the stripping device in the supply chamber which serves to unroll the film.

A preferred embodiment of the invention is illustrated by way of example in the accompanying drawings wherein

Fig. 1 is a plan view of a developing tank in accordance with the invention, whose cover has been removed,

Fig. 2 is a vertical section of the developing tank with the cover thereon, as the leading end of the film is being introduced into the film attaching means on the take-up axle,

Fig. 3 is the same view as in Fig. 2, however, showing the apparatus after the film end has been affixed and the winding thereof in a counterclockwise direction has begun, and

Fig. 4 is again the same view as in Figs. 2 and 3, but shortly after the reverse winding of the film, i. e. in clockwise direction, has begun.

The details of the apparatus and its opera-

tion can best be described simultaneously with reference to the foregoing figures. In the preliminary roll film supply chamber 1 adjacent the developing chamber 2 the roll film 3 is inserted, and the leading end of the paper protective strip 4 is placed between the lower cover portion 5 and the upper cover portion 6. The overlapping cover portions 5 and 6 close the developing tank in a lighttight manner, but the treating liquid can be introduced into and poured out of the developing chamber 2 through the trough 7.

In the roll film supply chamber 1 there is mounted a guide member 8, which resiliently grasps the roll film 3 at its edge portions. The upper end portion 8a of this guide member is so shaped that it serves as a stripping device for the film, while its other end is swingably mounted about the axle 9 (see Fig. 1). The projections 8b at the back of the guide member 8 help to support it and serve to guide the separated film into the developing chamber 2. The shape of these projections 8b is so chosen that the film is supported thereon only at its edge portions.

The partition 10 between the developing chamber 2 and the roll film supply chamber 1 prevents introduction of the treating liquid into the latter. A sliding support 11 is swingably mounted inside the developing chamber 2 at the axle 12 near the top of the partition 10 and reaches into the opening 13 of the film clamping means on the take-up axle 14 as shown in Fig. 2. By means of a projecting portion 12a of the axle 12 it is possible to raise the sliding support 11 from outside the tank. The opening 13 will receive the leading end of the film, which is then clamped to the take-up axle 14 by means of the resilient clamp jaw 15 having a toothed end 15a. A rotatable bowed rod 16 is also mounted in the take-up axle 14. When the axle is turned in a counterclockwise direction, the projecting end 16b of the bowed rod 16 strikes against a ledge 5a of the cover portion 5 whereupon the bowed portion 16a presses against the clamp jaw 15 and automatically effects a closure thereof. In order to prevent turning of the take-up axle 14 in the wrong direction, a projection 2b is provided inside the developing chamber 2 against which the projecting end 16b of the bowed rod 16 will strike. Furthermore, a peg 14b (see Fig. 1) is arranged at the end of the take-up axle 14 in the path of the end portion of the bowed rod 16, thus limiting its freedom of rotation in one direction.

A further clamping device 17 is mounted on the inner portion 5 of the cover and serves the purpose of clamping the trailing portion of the film against the sliding support 11, after the portion of the film to be developed has been wound upon the take-up axle 14, as shown in Fig. 4. When partly open (see Fig. 2) this clamping device 17 helps to guide the leading end of the film from above. The clamping device may be actuated from outside the tank by means of a projecting bent end 17a and can be held in its effective position by means of a wedge-shaped surface 18 (see Fig. 1).

The foregoing arrangement of parts results in the following mode of operation. After inserting the roll film 3 into the supply chamber 1 and closing the cover portion 5, the leading end of the paper protective strip 4 is placed over the cover portion 5 and the upper portion 6 of the cover is then placed thereover and over the supply chamber 1. The remaining parts, particularly the take-up axle 14, the sliding support 11 and the clamping device 17, are then brought

into the positions shown in Fig. 2. Thereupon one pulls out the paper protective strip 4 until one notices a sharp resistance. This resistance is caused by the leading end of the film 19 striking against the take-up axle 14 and clamp jaw 15, after being stripped from the roll film 3 by the stripping device 8 and guided over the projections 8b and the sliding support 11 through the opening 13 of the film attaching means. At this point the take-up axle 14 must be turned in a counterclockwise direction by means of the crank 20. Thereupon the projecting end 16b of the bowed rod 16 strikes against the ledge 5a of the cover portion 5. This causes the bow 16a to be forced against the clamping jaw 15, whereby the leading end of the film is automatically clamped against the take-up axle. Then the projecting end 16b is pushed within the groove 14a of the take-up axle 14, so that it will have no disturbing effect when winding up the film.

When beginning the winding in the counterclockwise direction, the end of the sliding support 11 is released by the take-up axle 14 and drops by its own weight against the inner wall 25 of the developing chamber 2, i. e., out of the film winding zone. Winding is continued until one notices a definite resistance, which occurs when the trailing end of the film that is attached to the protective paper strip 4 arrives at the cover portion 5. One then clamps the film end against the sliding support 11 by means of the clamping device 17 and holds that device in said position by coaction between the protruding portion 11a and the wedge-shaped surface 18. After the trailing end of the film is thus held, the direction of winding of the film may be several times reversed, until the development or other treatment has been completed. Upon reversing the winding to a clockwise direction, a wandering S-shaped bow is formed in the film as shown in Fig. 4. This bow assists in agitation of the treating liquid. After development of the film, the developing solution may be poured out of the container and replaced with fixing solution through the trough 7 without opening the cover, and the procedure then repeated.

It should be pointed out that the invention is not limited to daylight developing tanks that operate without the usual swingable guide and spirally grooved flanges. The automatic threading and clamping means for the leading end of the film is also useful in other types of developing tanks than the one specifically described. Many modifications of the details furnished will immediately be apparent to those skilled in the art. These are included within the spirit and scope of the invention and covered by the appended claims, except where excluded by express limitations therein.

What is claimed is:

1. A daylight developing tank for roll films having paper protective strips which comprises a roll film supply chamber, an adjacent developing chamber, a light tight, overlapping two-part cover for both with an opening between said parts for pulling out the paper strip, a partition between said chambers leaving an opening at its upper edge connecting the two, a rotatable take-up axle within the developing chamber bearing a clamp jaw for attaching the leading end of the film, a stripping device in the supply chamber for unrolling the film and guiding it to the developing chamber, and a swingably mounted sliding support in the developing chamber leading from

5

the opening between the chambers to the opening between the film clamp jaw and the axle.

2. A daylight developing tank as claimed in claim 1, wherein the take-up axle also bears a means for closing the clamp jaw that is actuated by striking a projection in the developing chamber when the axle is turned in a counter-clockwise direction.

3. A daylight developing tank as claimed in claim 2, wherein the means for automatically closing the clamp jam consists of a bowed rod having an end portion that strikes against a projection on the lowermost cover portion when turning the axle in a counterclockwise direction.

4. A developing tank as claimed in claim 2, provided with a film clamping means operable from outside of the tank, that holds the film at the opening between two chambers.

5. A daylight developing tank as claimed in claim 4, wherein the holding means consist of a swingable bowed rod whose bowed portion will bear against the sliding support that is mounted at the partition between the two chambers.

6. A daylight developing tank for roll films having paper protective strips, a roll film supply chamber and adjacent developing chamber within said tank, a partition between said chambers, a light-tight cover for both, an opening in the cover through which the paper protective strip may be pulled, wherein the take-up means within the developing tank include a take-up axle within the developing tank, forming a clamping means for the end of the film, and guiding means for directing and introducing the end of the film from the supply chamber between said clamping means, said guiding means including a stripping device for the film in the supply chamber with projections leading to the developing chamber and a swingable mounted sliding support leading from the top of the partition between the supply and the developing chambers into the mouth formed by the opened clamping means.

7. A daylight developing tank for roll films having paper protective strips, a roll film supply chamber and adjacent developing chamber within said tank, a partition between said chambers, a light-tight cover for both, an opening in the cover through which the paper protective strip

6

may be pulled, wherein the take-up means within the developing tank include a take-up axle within the developing tank, forming a clamping means for the end of the film, and guiding means for directing and introducing the end of the film from the supply chamber between said clamping means, said guiding means including a stripping device for the film.

5 for directing and introducing the end of the
film from the supply chamber between said
clamping means, said guiding means including
a stripping device for the film in the supply
chamber with projections leading to the develop-
10 ing chamber and a swingable mounted sliding
support leading from the top of the partition
between the supply and the developing chambers
into the mouth formed by the opened clamping
means, said sliding support being mounted on
15 an axle in the developing chamber adjacent to
the top of the partition between said chamber
and the supply chamber, and the other end of
the sliding support projects into the mouth of
the film opened clamping means of the take-up
20 axle and is supported thereby but released on
turning the axle in a counterclockwise direction.

8. A daylight developing tank for roll films having paper protective strips, a roll film supply chamber and adjacent developing chamber with-
25 in said tank, a partition between said chambers, a light-tight cover for both, an opening in the cover positioned to overlie the said developing chamber and juxtaposed opposite the roll film supply chamber immediately above said parti-
30 tion, and film supporting guide means normally positioned to extend between said chambers for directing the leading end of the film as a planar band from the supply chamber to a film attaching and winding means carried in the develop-
35 ing chamber, said guide means having a protective member stripping means integrally carried therewith and positioned in the path of the film as it unwinds from the roll film supply chamber including structure for directing said protective
40 paper to said opening in the cover while the film is being wound up on the film attaching and winding means.
